UNITED STATES PATENT OFFICE.

CHARLES E. SCRIBNER, OF JERICHO, VERMONT, AND JAMES L. MCQUARRIE, OF MONTCLAIR, AND EDWARD B. CRAFT, OF HACKENSACK, NEW JERSEY, ASSIGNEES TO WESTERN ELECTRIC COMPANY, OF NEW YORK, N. Y., A CORPORATION OF ILLINOIS.

SYSTEM OF SELECTIVE CONTROL.

1,071,588.

Specification of Letters Patent. Patented Aug. 26, 1913.

Application filed March 12, 1910. Serial No. 548,891.

To all whom it may concern:

Be it known that we, CHARLES E. SCRIBNER, JAMES L. MCQUARRIE, and EDWARD B. CRAFT, citizens of the United States, residing at Jericho, Chittenden county, Vermont; Montclair, Essex county, New Jersey, and Hackensack, Bergen county, New Jersey, respectively, have invented a certain new and useful Improvement in Systems of Selective 10 Control, of which the following is in full, clear, concise, and exact description.

Our invention relates to systems of selective control and its object is to provide improved means for selectively controlling apparatus at a plurality of stations associated with a line.

Our invention is particularly applicable to selective systems of the general type wherein the switch mechanisms, at the respective stations of a line, comprise switch members normally movable in definite phase relationship subject to the control of sending mechanism at a station on the line, as illustrated, for example, by selective systems of the type 20 employed in train despatching. In systems of the type mentioned, heretofore employed, electromotive forces impressed upon the line from extraneous sources may cause one or more of the switch mechanisms to operate 25 and advance the corresponding switch members, thereby bringing the members at the various stations into some other than their normal phase relationship. Or such extraneous electromotive forces may operate to 30 advance all of said members from their normal positions. In either case the substation apparatus would be left in other than its normal condition so that upon a subsequent 35 operation of the sending mechanism the switches at the various stations would operate abnormally, the result being a confusion of connections.

An important feature of our invention consists in the provision of means whereby 40 false operation due to current from an extraneous source is prevented. This is provided for by dividing the movement of the switch members into two parts, one of which may be termed the "preliminary" range of 45 movement, and preferably consists of but a single step, and the other of which may be termed the "selective" range of movement. The switch in our system may be so related 50 to the system that it can be advanced through

its preliminary range only by current of one 55 character and can be subsequently advanced through its selective range only by current of a different character. With this construction current from extraneous sources, whether constant or interrupted, will not 60 advance the switches at all if it is of one character, and if it is of the other character will at most advance them only through their preliminary range. In our system means are provided whereby the sending 65 mechanism may send initial current of one character adapted to advance the switches through their preliminary range, after which said mechanism will send current of a different character adapted to further advance 70 said switches. The sending mechanism is furthermore provided with means whereby when the switch members have been advanced to a position corresponding to any given station, a current of the same 75 character as the initial current may be impressed upon the line to bring a signal or other device into circuit. This last mentioned current, by reason of its character together with the fact that the switch members are at this juncture within their selective range of movement, will have no effect 80 upon the movement of the switch members.

From the above it will be apparent that in our invention the switch members if disturbed at all by extraneous sources of current are moved to but a slight degree from their normal positions. Also it is obvious that if the extraneous current is impressed upon the line at a point where it operates to 85 advance certain of the switch members only, thereby disturbing the phase relationship of the switch members throughout the system, such disturbed phase relationship will be corrected upon the operation of the sending 90 mechanism prior to the advance of any of the switch members through their selective 95 range proper.

In long lines heavily loaded with substation equipment, as the lines of a train 100 despatching system may be, efficiency in the matter of power consumption is particularly desirable. By our invention a substation switch of the type wherein the movable member rotates in a single direction may 105 be employed, thereby obviating the necessity of applying a restoring force to said member, the force of which would have to

be overcome in its operation, with consequent consumption of power. Switches of this general type are not a part of our invention, but their employment is rendered practical by our invention by reason of the feature already set forth whereby definite phase relationship may be maintained.

Other more specific features of our invention will be hereinafter set forth.

10 Our invention will be more readily understood by reference to the accompanying drawings, in which—

Figure 1 is a sender mechanism which may be used with the system of our invention; Fig. 2 is a side view, partly in section, of switch mechanism adapted for use at the substations; Fig. 3 is a front view of said switch mechanism; Fig. 4 is a rear view of said switch mechanism; Fig. 5 is a perspective view partly in section of the switch member and associated parts; and Fig. 6 is a circuit diagram showing a line equipped in accordance with the system of our invention, with sending mechanism and two sets 25 of substation equipment. Fig. 7 is a fragmentary sectional view showing details of the sending mechanism.

Like characters of reference are used to designate like parts throughout the several views.

Referring to Fig. 1, showing a sender mechanism adapted for use with our system, 7, 8 and 9 are parallel plates spaced in any suitable manner to form a frame or support 45 for the operating parts. Secured to the lower face of the plate 9 are two circular series of radially projecting contact members 10 and 11, each of said series being insulated from the other. The contact members comprising each series are, however, in electrical connection. 12 is a shaft rotatably carried by said plates 7, 8 and 9 and adapted to be driven through one rotation by the spring-actuated gear mechanism 13, 45 14 and 15, when the lever 16 is actuated to wind the driving spring of said mechanism. 17 is a brush or wiper arm carried by said shaft 12 and adapted, as it rotates therewith, to normally sweep over the members 11 of 50 the lower circular series and make successive contact therewith. As shown in the drawing, the circular series of members 10 is mounted in staggered relation to the lower series of members 11. All the members 10, 55 except the one designated in the drawing as 10', are however carried slightly above the members 11, whereby they are normally out of the path of the brush 17. Directly above the members 10 are keys 18, 19, 20, 21, etc., 60 one key for each said member 10. Each said key is slidably carried in the plates 7, 8 and 9 and is adapted, when operated, to depress the corresponding member 10, thereby bringing the end of said member into the 65 path of the brush 17. Each of said keys

comprises a spring member 22, carrying a latch 23 adapted, when said key is depressed, to engage the adjacent edge of the notch 24, within which notch said member 22 is guided. The end of the plunger of each key is provided with insulation 25 adapted to prevent its electrical connection with the member 10. In the drawing, key 19 is shown in its operated position, wherein it is locked as described. The member 10' may be fixedly carried in the path of the brush 17 and, for a purpose hereinafter explained, said member may be mounted in position to be engaged by the brush 17 during its initial movement. No key is therefore provided for said member 10'. The shaft 12 carries an arm 26 terminating in a member 27 adapted in its rotation to engage with the projecting end 28 of the spring member 22 of any key which may be depressed. The arm 26 is so positioned on the shaft 12 that the brush 17 is slightly in advance of the member 27, whereby said brush may make contact with any member 10 which may be depressed into its path before said member 27 reaches the projection 28 of the corresponding key. 29 is a plate or contact ring fixedly mounted and 30 is a brush carried by the shaft 12 and adapted to provide an electrical connection 95 of said plate 29 with the brush 17. 31, 32 and 33 are terminals in permanent electrical connection with the members 10, the members 11 and the ring 29, respectively, as clearly shown in Fig. 7. In order to more 100 clearly show the construction of the sender, the shaft and parts carried thereby are not shown in their normal positions in Fig. 1. Normally the parts mentioned lie in such a position that the brush 17 will make contact with the member 10' during its initial movement. The direction of rotation of the shaft is indicated by the arrow. 105

With the construction described, it is apparent that upon turning the lever 16 the 110 driving spring of the gear mechanism will be wound, thereby resulting in the rotation of the shaft 12 and parts carried thereby. The shaft will, during its initial movement, bring the brush 17 into electrical connection 115 with member 10' and then successively into connection with all the members 11 of the lower circular series and also with any of the members 10 of the upper series which may have been brought into its path by the 120 depression of a key. With the relation of parts as described, it will be obvious that after the brush 17 has passed a depressed member 10, the member 27 will engage the end 28 of the locking spring of said key, 125 thereby forcing said end in a radial direction and withdrawing the latch 23 from its engagement with the edge of the notch 24, whereby said key will be automatically restored. The mechanism therefore provides 130

means whereby a circuit extending from terminal 32 to the ring 29 may be completed once for each member 11 engaged by the brush 17, and whereby a circuit extending from terminal 31 to ring 29 may be completed once for each key depressed, the latter completions being interposed at will between any two of the former.

Referring to Figs. 2, 3, 4 and 5, showing a selector switch adapted for use with our system, 34 is a frame or mounting comprising the supports 35 and 36. An electromagnet comprising coils 37 is secured to support 36, said electromagnet being provided with an armature 39 pivoted between lugs 40. Mounted upon the frame 34 is a U-shaped auxiliary frame 41 comprising members 42 and 43, upon which latter the shaft 44 is rotatably carried. Fixed to the shaft 44 is a ratchet 45 adapted to be actuated by a stepping pawl 46 pivotally carried by the arm 47 secured to the armature 39. The armature is retracted by spring 48. The stepping pawl is kept in engagement with the ratchet by spring 49. Spring 50 serves as a holding pawl for the ratchet. Referring particularly to Fig. 5, the terminal structure of the switch comprises supporting plates 51 and 52 between which are clamped a continuous conducting ring 53, a conducting ring 54 which is continuous except for the terminal 55 electrically separated therefrom, two adjacent terminals 56 and 57 and members 58, 59 and 60 adapted to insulate the members mentioned. The parts referred to constitute a unit which may be secured to the member 43 of the U-shaped frame 41. Projecting from the members 53, 54, 55, 56 and 57 are the connection terminals 61, 62, 63, 64 and 65, respectively. Upon the shaft 44 are two sets of brushes, one set comprising brushes 66 and 67 adapted, in their movement, to connect ring 53 with ring 54 or with terminal 55, and the other set comprising brushes 68 and 69 adapted to connect terminal 56 with terminal 57. The brushes 66 and 67 are shown in their normal position in which they connect ring 53 with terminal 55. The brushes 68 and 69 are carried by a clamp member 70 which in turn is adjustably secured to the shaft 44 by means of clamping screw 71, whereby said brushes may be caused to normally bear any desired angular relation to the terminals 56 and 57 with which they engage. With the construction described, the energization of the electromagnet by impulses of current causes the advance of the ratchet one step for each impulse, thereby causing the brushes 66 and 67 to move from their normal position, wherein they connect ring 53 with terminal 55, to some other position, in any of which other positions they may join ring 53 with ring 54. In the advance movement of the

ratchet, the brushes 68 and 69 will obviously connect terminal 56 with terminal 57 at some stage of said movement depending upon the angular relation of said brushes to said terminals.

Referring to Fig. 6, showing an embodiment of our invention in a selective signaling system, 72 is the sending station which in practice might be the office of a train despatcher. At said station the sending mechanism, already described, is located, said mechanism being so connected in circuit that the brush 17 is in connection with one limb 73 of the line and the two series of members 10 and 11 are, respectively, connected with opposite poles of batteries 74 and 75, the remaining poles of said batteries being connected to the remaining limb 76 of the line. The despatcher's telephone set 77 may be bridged across the line as shown, impedance coils 78 and 79 being inserted in the line between the batteries 74 and 75 and said set 77 as a means of preventing undue disturbance of the telephone of said set by selecting impulses. In the drawing, two way or substations 80 and 81 are shown associated with the line, the apparatus at said stations being connected in parallel with the line. The equipment at each station may comprise, in addition to the selector switch already described, other switching mechanism including a polarized relay 82, a locking relay 83, a key 84 and a bell, buzzer or other signal 85. The mechanism may derive its operating power from a battery 86. The armature 87 of the polarized relay 82 may normally be held in its mid position by springs 88 and 89 engaging with stops 90 and 91, respectively, whereby current of one polarity will cause said armature to tilt in one direction and engage contact 92, and current of the reverse polarity will cause said armature to tilt in the opposite direction and engage contact 93. One pole of the battery 86 is connected by conductor 94 with the operating magnet 37 and thence, through conductor 95, with the ring 53 of the switch, whereupon two parallel paths to the polarized relay 82 are provided, one of which paths is completed by brushes 66 and 67 in their normal position as shown in the drawings, whereby the circuit thus partially traced is extended from ring 53 through said brushes to terminal 55, thence through conductor 96 to normally open contact 92 of relay 82, thence through armature 87 and conductor 97 to the battery 86. In the normal position of the brushes 66 and 67, the circuit just traced through the operating magnet 37 will therefore be completed by the polarized relay 82 when said relay is energized by current of such polarity as to cause its armature to tilt in a clockwise direction and in no other position of said brushes will said electromagnet 37

be operated by such operation of the polarized relay 82. The remaining parallel return path for the circuit through the operating electromagnet is from ring 53 through 5 brushes 66 and 67, conductor 98, normally open contact 93, armature 87 and conductor 97 to the battery. This circuit is normally open and can therefore only be completed by the polarized relay when the brushes 66 10 and 67 are in some other than normal position. The operating electromagnet may therefore be energized by the completion of either of the above described circuits and therefore may be energized by current of 15 either polarity through the relay 82. It will be observed, however, that each of the local operating circuits is subject to both the selector switch and the polarized relay and can be completed only under certain conditions 20 with respect to both the polarity of the line current through the relay 82 and the position occupied by the brushes 66 and 67 at the instant in question and that said condition may be such that at no time will 25 the energization of the relay 82 by current of other than one polarity result in the operation of the electromagnet 37. With the arrangement described, it will be apparent that with the brushes 66 and 67 in their 30 normal positions, said brushes cannot be caused to move more than a predetermined distance from normal by successive line impulses, and that even this movement is possible only when the line current is of predetermined 35 polarity. In the drawings the structure is such that said predetermined distance is limited to one step.

Referring to the circuit controlled by the switching mechanism, a circuit is shown 40 including a signal 85. This circuit is shown as extending from battery 86 through conductor 99, signal 85, normally open terminals 56 and 57, conductor 100, conductor 96, normally open contact 92, armature 87 of 45 relay 82, and conductor 97 to the other pole of the battery 86. In parallel with the signal 85, a locking relay 83 may be provided, whereby when the circuit of the bell is completed, that of the relay is also. The locking circuit of the relay 83 extends from 50 battery 86 through conductor 99, conductor 101, the winding of said relay 83, locking contact 102 and armature 103 of said relay 83, key 84 through conductor 105, to the remaining pole of the battery. With the 55 structure described, the brushes 68 and 69, after having been moved the required number of steps from normal, will engage with terminals 56 and 57 and thereby prepare 60 the circuits of the signal 85 and relay 83 for completion by the polarized relay 82, which latter relay will respond to a current of proper polarity to tilt its armature in a clockwise direction and thereby com-

plete said circuits. It will be observed that 65 under the conditions existing at this juncture, the operation of the polarized relay in a clockwise direction produces no effect upon the other circuits. The circuits of the 70 buzzer and locking relay having been completed as described will remain complete through the locking circuit, already traced, until key 84 is operated to open said circuits. Obviously, except for the locking means, the bell would operate only during 75 such time as the brushes 68 and 69 remained upon terminals 56 and 57. Under certain conditions this, however, might be sufficient. It will be understood that in the switches at 80 the respective stations, the brushes 68 and 80 69 will be carried upon the shafts at different angular positions with respect to the brushes 66 and 67, whereby the buzzer circuit is prepared for completion at but one 85 station at a time as the switches advance in synchronism.

The operation of our invention may be described as follows: Let it be assumed that the operator at sending station 72 wishes to signal station 81 and that in the switch at 90 said station the brushes 68 and 69 are so placed with respect to brushes 66 and 67 that three steps are required to bring the former into engagement with terminals 56 and 57. The operator at the sending station 95 will depress that key of the sender which will bring a member 10 into the path of the brush 17 between the second and third of the members 11. Upon turning the lever 16 in a direction to wind the driving spring and then releasing the same, the shaft 12 will rotate through one complete rotation, the brush 17 first engaging member 10', whereupon battery 74 is connected with the line, thereby resulting in the operation in a 105 clockwise direction of the polarized relays 82 at all stations. The operation of said polarized relays causes the completion of the operating electromagnets 37 at all stations, whereby the switch brushes are advanced one step. The sender brush having 110 passed member 10' next engages two members 11 in succession, whereby battery 75 is momentarily connected with the line twice. As a result, two impulses of current 115 of such polarity as to operate the polarized relays 82 in a counterclockwise direction are impressed upon the line. The operation of the polarized relays twice as described advances the brushes at all stations two 120 steps, whereupon brushes 68 and 69 of station 81 are brought into engagement with terminals 56 and 57, thereby preparing the circuits of the signal 85 and locking relay 83 for completion by a reversed operation 125 of polarized relay 82. This reversed operation is provided for by the key referred to above as having been depressed, whereby

the brush 17 coming in contact with the member 10 depressed by said key, connects battery 74 with the line, thereby momentarily completing the circuit of the bell and locking relay at station 81. Said circuit will, as already explained, be locked subject to the operation of key 84. The bell and locking circuit will of course be completed by the impulse under consideration only at station 81 by reason of the fact that at this station only are the brushes 68 and 69 in contact with terminals 56 and 57 at this juncture.

From the above it will be readily understood that if impulses of current of one polarity be impressed upon the line, said impulses will operate each of the switches through its preliminary range only, which preliminary range, in the system shown herein, comprises but one step, although not necessarily so limited. Furthermore, said impulses may be of either polarity without advancing the switches through more than said preliminary range. They may, moreover, act upon part of the circuit only whereby they might advance certain of the switches through their preliminary range without affecting others. This, however, would not result in false signaling by reason of the fact that the sender is provided with one or more members 10', whereby said sender impresses one or more preliminary impulses upon the line during its initial operation, the number depending upon the extent of said preliminary range, and therefore would bring any displaced switches into proper phase relationship before actuating all of the switches.

While we have described a form of our invention in which a current of one polarity is adapted to control the movement of the switch members through the preliminary range and a current of a reverse polarity is adapted to move such switch members through their selective range, it must be understood that our invention is not limited to the use of a polarized relay nor to the use of current of opposite polarities but covers broadly the use of any suitable currents of different characters and a relay controlling the switch members distinctively responsive to such currents.

We claim:—

1. The combination with a line, of a source of current at a station on said line, sending mechanism for impressing currents of different character upon said line, switch mechanism at each of a plurality of stations on said line, said switch mechanism being adapted to be advanced through a preliminary range of movement under control of current of one character and through a further range under control of current of another character, and means coöperating with

said switch mechanism for preventing the advance of said switch through more than said preliminary range under control of current of either one character alone.

2. The combination with a line, of a source of current at a station on said line, sending mechanism for impressing positive and negative current upon said line, switch mechanism at each of a plurality of stations on said line, said switch mechanism being adapted to be advanced through a preliminary range of movement under control of current of one polarity and through a further range under control of impulses of reversed polarity, and means coöperating with said switch mechanism for preventing the advance of said switch through more than said preliminary range under control of successive impulses of either one polarity alone.

3. The combination with a line, of a source of current at a station on said line, sending mechanism for impressing currents of different character upon said line, switch mechanism at a plurality of stations on said line controlled by currents of different character, said switch mechanism comprising a member having a mechanism comprising a member having a preliminary range of movement and a selective range of movement, and means coöperating with said switch mechanism whereby current of one character adapted to control movement of said member through one range will be ineffective for controlling movement through said second range.

4. The combination with a line, of a source of current at a station on said line, sending mechanism for impressing positive and negative current upon said line, switch mechanism at each of a plurality of stations on said line controlled by said positive and negative current, said switch mechanism comprising a member having a preliminary range of movement and a selective range of movement, and means coöperating with said switch mechanism whereby current of polarity adapted to control the movement of said member through one range will be ineffective in controlling the movement through said second range.

5. The combination with a line, of a source of current at a station on said line, sending mechanism for impressing impulses of current of different character upon said line, and a selector switch mechanism comprising a movable member at each of a plurality of stations on said line, said switch mechanism being adapted in a selecting operation to advance in response to initial current of one character and subsequently in response to current of another character only.

- 6 The combination with a line, of a source of current at a station on said line, sending mechanism for impressing positive and negative impulses of current upon said line, and selector switch mechanism comprising a movable member at each of a plurality of stations on said line, said switch mechanism being adapted in a selecting operation to advance in response to initial current of one polarity and subsequently in response to current of reversed polarity only. 7. The combination with a line, of a source of current at a station on said line, sending mechanism for impressing positive and negative current upon said line, mechanism comprising a movable switch member at each of a plurality of stations on said line; a circuit controlled by said member at a predetermined position, said mechanism operating in response to current of one polarity to cause the initial advance of said member and in response to current of reversed polarity only to cause the subsequent advance of said member to said position. 8. The combination with a line, of a source of current at a station on said line, sending mechanism for impressing positive and negative current upon said line, mechanism comprising a movable switch member at each of a plurality of stations on said line, a circuit controlled by said member at a predetermined position, said mechanism operating in response to current of a given polarity to cause the initial movement of said member, in response to current of reversed polarity only to cause the subsequent movement of said member, and in response to current of said given polarity to control said circuit. 9. The combination with a line, of a source of current at a station on said line, sending mechanism for impressing positive and negative current upon said line, mechanism comprising a movable switch member at each of a plurality of stations on said line, a circuit controlled by said member at a predetermined position, a signal controlled by said circuit, said mechanism operating in response to current of a given polarity to cause the initial movement of said member, in response to current of reversed polarity only to cause the subsequent movement of said member, and in response to current of said given polarity to control said circuit. 10. The combination with a line, of a source of current at a station on said line, sending mechanism for impressing positive and negative current upon said line, mechanism comprising a movable switch member at each of a plurality of stations on said line, a circuit controlled by said member at a predetermined position, a relay controlled by said circuit, and a signal controlled by said relay, said mechanism operating in response to current of a given polarity to cause the initial movement of said member, in response to current of reversed polarity only to cause the subsequent movement of said member, and in response to current of said given polarity to control said signal. 11. The combination with a line, of a source of current at a station on said line, sending mechanism for impressing positive and negative current upon said line, a polarized relay at each of a plurality of stations on said line, a switch at each of said plurality of stations, an electromagnet for operating said switch, a circuit controlled by said switch at a predetermined position, a signal controlled by said circuit, a contact in said circuit controlled by said relay, a circuit for said electromagnet controlled jointly by said switch and said relay, said circuit being completed, when the switch is in its normal position, by current in the line of one polarity and by current of the reversed polarity when the switch is in other than its normal position. 12. In a selective signaling system, the combination with a line having a sending station and a plurality of way stations connected therewith, of mechanism at said sending station for impressing currents of different character upon said line, a step-by-step selective device at each of said way stations embracing an electromagnet, an operating circuit for said electromagnet having two branches, and a circuit closing device connected with the line at each of said way stations and operated by the currents of different character over said line to close the two branches of said operating circuit respectively. 13. In a selective signaling system, the combination with a line having a sending station and a plurality of way stations connected therewith, of mechanism at said sending station for impressing currents of different character upon said line, a step-by-step selective device at each of said way stations embracing an electromagnet, an operating circuit for said electromagnet having two branches, and a polarized relay connected with the line at each of said way stations adapted in response to current of one character to close one branch of said operating circuit and in response to currents of another character to close the other branch of said operating circuit. 14. In a selective signaling system, the combination with a line having a sending station and a plurality of way stations connected therewith, of mechanism at said sending station for impressing currents of different character upon said line, a step-by-step selective device at each of said way stations, a switching device at each of said way stations responsive to the currents of different character impressed upon the line at the sending station, and an operating

- circuit for said selective device having two branches each jointly controlled by said switching device and said selective device.
15. In a selective signaling system, the combination with a line having a sending station and a plurality of way stations connected therewith, of mechanism at said sending station for impressing currents of different character upon the line, a step-by-step selective device embracing an electromagnet and a movable member at each of said way stations, a circuit closing device connected with the line at each of the way stations responsive to the different character currents impressed upon the line at the sending station, and an operating circuit for said electromagnet embracing two branches one of which is closed when the movable member thereof is in one position and current of one character is sent over the line, and the other branch of which is closed when the movable member thereof is in another position and current of another character is sent over the line.
25. 16. In a selective signaling system, the combination with a line having a sending station and a plurality of way stations connected therewith, of mechanism at said sending station for impressing currents of different character upon the line, a step-by-step selective device, embracing an electromagnet, a movable member and circuit closing contacts controlled by said movable member, located at each of said way stations, a polarized circuit closing device connected with the line at each of said way stations and responsive to the currents of different character impressed upon the line at the sending station, and an operating circuit for said electromagnet comprising two branches one of which is closed only when the movable member thereof is in a given position and current of one character is sent over the line and the other of which is closed when said movable member is in other than the first mentioned position and current of a different character is sent over the line.
40. 17. The combination with a line, of a source of current at a station on said line, sending mechanism for impressing currents of different character upon said line, an electromagnetically controlled switch at each of a plurality of stations on said line, an actuating circuit for said switch comprising two branches, said branches being alternately rendered operative during the operation of the switch, a relay adapted to operate in response to current of one character to complete one of said branches when the switch is in its normal position and operate in response to current of another character to complete the other of said branches when the switch is in other than its normal position, and a second circuit jointly controlled by said switch and relay at a predetermined point in the advance movement of said switch.
18. The combination with a line, of a source of current at a station on said line, sending mechanism for impressing positive and negative current upon said line, an electromagnetically controlled switch at each of a plurality of stations on said line, an actuating circuit for said switch comprising two branches, said branches being alternately rendered operative during the operation of the switch, a polarized relay adapted to operate in response to current of one polarity to complete one of said branches when the switch is in its normal position and to operate in response to current of the reversed polarity to complete the other of said branches when the switch is in other than its normal position, and a second circuit controlled jointly by said switch and relay at a predetermined point in the advance movement of said switch.

In witness whereof, we hereunto subscribe our names this 11th day of March A. D., 1910.

CHARLES E. SCRIBNER.
JAMES L. McQUARRIE.
EDWARD B. CRAFT.

Witnesses:

IRVING MACDONALD,
MORGAN WASHBURN, Jr.
